UNITED STATES PATENT OFFICE.

WILLIAM E. WIER, OF GRAND RAPIDS, MICHIGAN.

TYPEWRITER ATTACHMENT

Application filed May 8, 1922. Serial No. 559,468.

To all whom it may concern:

Be it known that I, WILLIAM E. WIER, a citizen of the United States, residing at Grand Rapids, in the county of Kent and State of Michigan, have invented certain new and useful Improvements in Type-writer Attachments, of which the following is a specification.

My invention relates to improvements in typewriters, and its objects are: first, to provide a means whereby a long sheet, or long sheets of paper may be used in writing with the machine; second, to provide a means whereby a large number of letters may be written without the necessity of replacing sheets of paper for each letter; third, to provide a means whereby briefs may be written without breaking them up in pages, and without changing sheets with each page of brief written; fourth, to provide a means whereby several sheets of paper with carbon paper properly intervened, may be written upon without the necessity of changing sheets and carbon with each page of writing; and, fifth, to provide for properly storing the carbon sheets as the writing is being done.

I attain these objects by the mechanism and distribution of parts shown in the accompanying drawing, in which Fig. 1 is an end elevation of a writing machine with my appliance in place. Fig. 2 is a back elevation of my appliance detached from the machine. Fig. 3 is a plan of a typewriting machine with my device in place. Fig. 4 is a plan of one end of the roller upon which carbon paper is to be stored after having written with it, showing spring clamps for holding the edge of the carbon paper in place while being wound around the roller or shaft. Fig. 5 is a like view of the other end of said shaft or roller. Figs. 6 and 7 show a copy holder attachment in place.

Similar reference characters indicate similar parts throughout the several views.

In the accompanying drawing 1 represents a typewriting machine, 2 is the carriage that carries the platen 14, upon which the printing is done. 3 represents the side pieces or frame upon which the several working parts of my device are mounted. This frame has an integral cross piece, 3', at the bottom thereof, and a cross brace 3'' well up upon the frame. At the lower end 65 of this frame I mount two rollers, 4, as in-

dicated in Fig. 2, to provide for the easy and ready movement of this device with the carriage and platen of the machine as type writing is being done. At 6 I have shown a reel upon which the writing paper is to be stored, said reel being mounted upon the shaft 7 and made to revolve for winding the paper upon it by means of the crank 7', or its equivalent.

The arms 8 are designed to be secured to the bearings *a* on the carriage in such a manner that the movements of the carriage will be transmitted to the frame 3 and will hold the reel 6 always in proper alinement with the carriage as the carriage travels longitudinally of the machine frame in the act of writing or printing upon the paper.

In winding the paper upon the reel the writing paper and the carbon paper are laid in alternate layers, as is usually done in manifold work, except that in this instance very long sheets of paper, and of carbon are used, instead of the usual short sheets.

To complete this device, I mount several shafts, 12, in the frame sides 3 so that they may be readily removed, replaced and made to revolve freely, and place a driving pulley or sheave, as 9, 10, 11, upon one end of each shaft in such a position that a belt passed over these pulleys and over the pulley 15, which is directly mounted upon the platen shaft 14', so that every time the platen is made to revolve its action upon the belt 16 will cause the shafts 12 to revolve accordingly. The shafts 12 are provided with clasps 13' between which and the surface of the shaft the ends of the carbon sheets are secured so that these shafts will be made to take up the carbon sheets as fast as they are passed over the platen, thus separating the carbon sheets from the printed sheets, storing the carbon sheets, and passing the printed sheets over and between the shafts 12 into position back of the machine, as indicated at *c*, *d*, *e* and *f*, in Fig. 1. In passing from the reel 6 upon the platen 14, the paper passes over the guard *h*, back of the platen, in the several folds, as shown in Fig. 1. The reference character *g* represents the carbon sheets as they pass from the platen 14 upon the shafts 12, and the manner of securing these sheets to the shafts 5 is plainly illustrated in Figs. 4 and 5, the two figures showing the two ends of what should be a continuous shaft, which, in full size as

shown, would be too long to show as a complete shaft upon the drafting sheet, hence the divided shaft shown in Figs. 4 and 5.

At 5 I have shown the yokes into which the rollers or wheels 4 are revolvably mounted, which said yokes are securely connected with the cross bar 3' of the frame 3, by means of the bolts and nuts *i*, or other suitable supporting elements.

It will be readily understood that with this line of construction and with the several connecting elements, the frame 3-3' and its several elementary parts must move uniformly with the carriage 2 in its movements longitudinally of the machine frame, and, practically, without friction, and the paper must be withdrawn from the reel 6 with every revoluble movement of the platen or writing roller 14, so that the movements of the machine are fully as free and unencumbered as if this appliance were not in use, and the advantages gained by the limitless amount of writing that may be done without changing sheets are almost incalculable.

While the frame of the auxiliary carriage 3-3' is made separate from the machine frame or carriage, it is so directly connected with the machine carriage as to become absolutely auxiliary thereto, and to be made to move, at all times, in actual unison with the machine carriage.

The clamping fingers 13' should be made adjustable longitudinally of the shafts 13 so they may be adjusted to different widths of paper, as indicated by the dotted lines on Fig. 4.

In Figures 6 and 7 I have shown an end view, and a front view, respectively, of my device with an adjustable copy holder attachment, consisting of the attaching bar 18, which is secured to the side pieces of my frame, as indicated at *j*, and to the upper ends of said bars I pivotally mount the copy holder 15, as indicated at *k*, so that it may be made to stand at various inclines from the perpendicular, as desired, and as indicated by the dotted lines in Fig. 6.

This copyholder is provided with clamping bars 16 intended to engage the sheets of copy and hold them safely while being copied from upon a typewriter machine. These clamps are made adjustable longitudinally of the copyholder by being mounted

upon bolts that pass through, and are adjustable, longitudinally, in the slots 17 so the said clamps may be adjusted to meet any width of copy paper that it is found necessary to use.

I prefer that the clamps 16 be mounted upon slideable supports *m*, placed in the slots 17, so it will not be necessary to loosen any screws or bolts when desiring to shift the clamps from one position into another position as varying widths of paper may demand.

At 19 I have shown a weight or latch pivoted to the frame 3 at *n*, and designed to rest upon the upper sides of the ends of the shafts 12 to avert the danger of said shafts being raised out of their bearings by the tension of the belt 16 when operating the machine.

Having thus fully described my invention, what I claim as new in the art, is:

1. In combination with a typewriting machine, and an auxiliary carriage having a reel arranged to carry writing paper and carbon paper and to feed such paper properly to the platen on the machine, said auxiliary carriage arranged to move longitudinally of the machine with the corresponding movements of the platen, shafts revolvably mounted upon said auxiliary carriage for receiving and storing each used sheet of carbon paper separately from the others, a pulley mounted upon the end of each of said shafts and a corresponding pulley mounted upon the platen shaft, a belt engaging said pulleys in such a manner that the revoluble movements of the platen will revolve all of said shafts, said shafts so arranged that the several used sheets of carbon paper may be automatically separated from each other after printing, and each sheet stored upon its respective shaft and the printed paper may be stored separately from the carbon paper.

2. In combination with the elements covered in claim 1, spring clamps mounted upon the shafts on the auxiliary carriage for clamping the ends of the carbon paper.

3. In combination with the elements covered in claim 1, an adjustable copy holder pivotally mounted upon and movable with my auxiliary carriage and forming close frictional connection therewith at the pivotal bearings.

WILLIAM E. WIER.
